UNITED STATES PATENT OFFICE.

HARVY SEGUR, OF DECATUR, INDIANA, ASSIGNOR OF ONE-HALF TO
JOHN WATTS, OF SAME PLACE.

CARPET-STRETCHER.

SPECIFICATION forming part of Letters Patent No. 290,274, dated December 18, 1883.

Application filed October 11, 1883. (No model.)

To all whom it may concern:

Be it known that I, HARVY SEGUR, a citizen of the United States, residing at Decatur, in the county of Adams and State of Indiana, 5 have invented a new and useful Carpet-Stretcher, of which the following is a specification, reference being had to the accompanying drawings.

This invention relates to carpet-stretchers; 10 and it has for its object to produce a device which shall possess superior advantages in point of simplicity, durability, and general efficiency.

To this end it consists in certain improvements in the construction of the same, which 15 will be hereinafter fully described, and particularly pointed out in the claims.

In the drawings hereto annexed, Figure 1 is a perspective view of my improved carpet-stretcher. Fig. 2 is a longitudinal vertical 20 sectional view of the same, and Fig. 3 is a detail view.

The same letters refer to the same parts in all the figures.

25 A in the drawings designates a rod or bar having at one end a point or prong, B, adapted to be driven into the floor adjacent to the wash-board. The upper side of said rod or bar is provided with teeth or ratchets C C.

30 D is a plate provided with downwardly-extending curved points or barbs E E, and having a laterally-extending arm, F. The said plate D and arm F are provided on their upper sides with bails or keepers G, in which the bar A may slide, as shown. The plate D is provided with a bail or bracket, H, extending over the arm F. To the said bracket is pivoted a lever, I, the lower end of which forms a pawl, J, engaging the ratchet-bar A, with 35 which it is held in engagement by the elasticity of the bracket H, which should be made of steel or other elastic material which is sufficiently strong for the purpose.

To the lever I, above its fulcrum, is pivoted 40 a dog or pawl, K, which also engages the ratchet-bar A.

The upper end of the lever I has a tapering dovetailed groove or recess, L, to receive a handle, by which it may be manipulated. This handle in the present case consists of a 50 tack-hammer, M, the lower end of the handle N of which is wedge-shaped, as at O, to enable it to be fitted in the recess L. The hammer-handle N is preferably made of metal, and its lower wedge-shaped end is provided with a 55 laterally-extending arm, P, provided with a notch, Q, for drawing tacks.

The operation of this invention and its advantages will be readily understood from the foregoing description, taken in connection 60 with the drawings hereto annexed. It is simple, convenient, inexpensive, easily manipulated, and it comprises, in a simple form, an apparatus for stretching a carpet to any desired extent, for holding it when stretched, and 65 for driving and drawing tacks.

I claim as my invention and desire to secure by Letters Patent of the United States—

1. The combination of a ratchet-bar having a prong at one end, a plate having curved 70 teeth, a laterally-extending arm, upwardly-projecting keepers, and a spring-bracket, a lever pivoted to said spring-bracket and having a pawl at its lower end, and a dog or pawl pivoted to said lever above its fulcrum, sub- 75 stantially as and for the purpose set forth.

2. The combination, with the operating-lever having a tapering dovetailed recess at its upper end, of a handle wedge-shaped at its lower end to enter said recess, and equipped 80 with a tack-hammer at its upper end, and at its lower end with a laterally-projecting bracket having a notch for drawing tacks, as set forth.

In testimony that I claim the foregoing as 85 my own I have hereto affixed my signature in presence of two witnesses.

HARVY SEGUR.

Witnesses:

JOHN T. FRANCE,
M. J. HOSLER.
